UNITED STATES PATENT OFFICE.

CHARLES K. WOODBRIDGE, OF FLUSHING, NEW YORK, ASSIGNOR TO DICTAPHONE CORPORATION, OF BRIDGEPORT, CONNECTICUT, A CORPORATION OF NEW YORK.

CONTAINER.

Application filed May 29, 1923. Serial No. 642,217.

This invention relates to improvements in containers or cartons, and, in some of its aspects, more particularly to containers for holding sound-records, such as are used 5 with dictating machines.

An object of this invention is to prevent scratching of the recording surface of a record both during the removal from, and replacement in, the container; and while 10 transporting the record therein.

It has been found, in practice, that dust and grit frequently accumulate upon the surface of the container adjacent its mouth, and that the record is sometimes seriously 15 scratched or marred while being slid into and out of it, especially when the record substantially fits the container. To avoid this difficulty, a suitable lining of any soft material, such as the usual lining of flannel, which is secured within the container to substantially cover its entire inner surface, is made long enough to extend beyond the mouth of the container and is folded over its edge. This covered edge prevents 20 the record from coming in contact with the container; and the nature of the material allows foreign matter lodged upon the lining, to sink into it without scratching the record.

30 Another object of the invention is to provide a sufficient bevel to act as a guide at the mouth of the container, to facilitate the insertion of the record.

Another object of the invention is to provide means enabling the discharge from the container of any foreign matter which might fall into it or be carried into it by the record, and which might result in marring the delicate surface of the record.

40 Another object is to enable the contents of the container to be viewed without removing its cover.

Another object is to reduce the cost of manufacture without diminishing the efficiency, strength, or durability of the container.

Another object is to provide for cushioning the fall of a record when dropped into the container to prevent injury, due to the 50 fragile nature of such records.

Another object is to provide a container in which the walls will be sufficiently rigid to prevent collapse or mutilation through accident during handling.

55 In the drawings—

Fig. 1 is a vertical sectional view of one embodiment of this invention, in which the bottom is perforated;

Fig. 2 is a bottom plan view thereof;

Fig. 3 is a vertical sectional view of another embodiment of this invention, in which the bottom is solid; and

Fig. 4 is a top plan view thereof with the cap, which is shown in Fig. 3, removed.

Similar reference characters indicate corresponding parts throughout the several figures of the drawings.

Referring to the drawings, and more particularly to Figs. 1 and 2 thereof, the embodiment of the invention shown is in the form of a cylindrical container, although it will be understood that such shape is not essential to the invention, which in its broader aspects relates to a receptacle suitably formed to accommodate any shape of article.

The body of the container comprises a tubular exterior portion or shell 10, of suitable material—as, for instance, stiff cardboard—within which there is secured, by pasting or otherwise, an inner cardboard tube 11. The upper edges of the tube 11 and shell 10 are flush, but the lower edge of the shell 10 extends below the tube 11 and its end portion is turned inwardly and upwardly to engage the under surface of a bottom 12 and hold it to the lower edge of the tube 11. This connection of the bottom 12 to the body of the container eliminates pasting, or otherwise securing the bottom 12 to the relatively narrow lower edge of the tube 11, and therefore, makes possible the use of a simple, flat stamping 19 for the bottom of the container and thereby materially reduces the cost of manufacture of the container.

By curling the turned-up part of the shell 10, so as to form a shock-absorbing annular rim or bead 20, the container is particularly adapted for use with fragile articles such as sound-records which, if carelessly dropped into the container, might otherwise be damaged. The bead 20 itself forms a shock absorber and yields sufficiently on impact to break the fall of the record without damaging it. Moreover, the particular style of connection shown permits the bottom to flex under the blow of the falling record, and thus assist the bead 20 in its function.

The mouth of the container is shown as closed by a suitable cap 17.

It should be understood, that in the application and use of the lining, and especially of the protected edge, it is not essential that the container be constructed as above described, but that the lining may be applied, within the scope of this invention, to containers of other forms and constructions.

10 The folded edge of the lining forms a sufficient bevel to serve as a guide or deflector for facilitating the insertion of the record.

The folded-over lining permits a cylinder record of wax or other easily damageable material, to be readily slid into and out of the container without any danger of engaging the body portion thereof, and without being scratched thereby, or by particles of dust lodged thereon. At the same time, 20 the lining encloses the edge of the tube 11 so that there is no possibility of particles of the tube breaking off and falling within the container.

The container is of sufficient rigidity to 25 withstand any ordinary pressure that it may encounter, and the several parts thereof are so constructed and arranged that they will not become deranged, and will be durable in use.

30 The bottom 12, as illustrated in Figs. 1 and 2, has a hole or opening 18 which permits anything, falling into the container or carried therein by the record, to drop directly through the hole, and not remain to scratch or mar the surface of the record.

The provision of the hole 18 is also advantageous, in that it exposes to view the contents of the container.

In Figs. 3 and 4, a modified form of the 40 invention is shown. In this case the tube 11 extends beyond the end of the shell 10 and there receives a cap-like bottom 12, which is slid over it and which is secured to it, preferably, by an adhesive.

45 It should be understood, that the form shown in Figs. 3 and 4 may be perforated at its base, if desired, and that the form shown in Figs. 1 and 2 may be solid—this feature of the invention being equally well 50 applicable to either of the embodiments of the invention shown.

The carton, according to the present invention, affords a maximum of protection to the article contained therein, is dust-proof, and permits insertion or removal of the 55 article without danger of scratching or otherwise marring its surface.

There are herein disclosed preferred and satisfactory embodiments of the invention, but changes may be made therein within the 60 spirit and scope thereof, as defined in the appended claims. It should also be noted that this invention also embraces the provision of the lining, per se, as defined, in condition to be affixed or applied to the 65 container.

It should be understood that the term "sound-record", as used herein, is intended to include sound reproducing as well as sound recording and reproducing records, 70 such as are used in dictating machines.

Having now described the invention, what is claimed as new, and for which it is desired to protect by Letters Patent, is as follows:

75 1. In a container, an inner body portion, an outer body portion, a lining secured to the inner body portion and folded over its edge and inserted between the adjacent surfaces of the inner and outer body portions 80 to form a protective facing for the entrance-edge of the inner body portion, the adjacent surfaces of the inner and outer body portions, engaged by the folded-in lining, being recessed to receive the lining without displacement of the surfaces.

85 2. In a container, an inner body portion; an outer body portion; the top edges of said portions being in alinement; a lining 90 secured to the inner body portion and folded over the top edge and inserted between the adjacent surfaces of the inner and outer body portions; said outer body portion being uncovered so that the folded over portion of the lining extends beyond the 95 edge of the outer body portion to protect articles entering the container from engagement with the outer body portion.

98 Signed at Bridgeport, in the county of Fairfield and State of Connecticut, this 25th day of May A. D. 1923.

CHARLES K. WOODBRIDGE.
